ROTOR CONSTRUCTION FOR ROTARY REGEN-
ERATIVE HEAT EXCHANGERTed C. Evans and Charles A. Lyle, Wellsville, N.Y., as
signors, by mesne assignments, to Combustion Engi-
neering, Inc., a corporation of Delaware

Filed July 17, 1959, Ser. No. 827,774

1 Claim. (Cl. 165—7)

This invention relates to rotary regenerative heat exchange apparatus and particularly to an arrangement that substantially precludes its thermal distortion during periods of normal operation.

In rotary regenerative heat exchange apparatus a cylindrical rotor having sectoral compartments provided by radial partitions or diaphragms that connect a central rotor post to a concentric rotor shell is adapted to carry a mass of regenerative heat exchange material. The rotor is adapted for rotation in such a manner that the heat exchange material is first exposed to a heating fluid to absorb heat therefrom, and as the rotor is turned about its axis, the heat exchange material is then disposed in a passageway for a fluid to be heated where the heat absorbed by the heat exchange material is imparted to the fluid flowing therethrough.

During operation such apparatus is continuously subjected to varying degrees of temperature whereby variations of thermal expansion resulting therefrom produce a warping and twisting of the rotor and its surrounding housing that generally precludes an efficient sealing of one fluid from another.

This invention is directed to a rotary regenerative heat exchanger having a structural arrangement such that temperature variations thereof induce substantially constant expansion or contraction that results in a minimum of distortion.

The heat exchange apparatus particularly referred to in this application comprises an improvement to the type generally described in U.S. Patent 2,680,008, issued June 1, 1954 to Per Hilmer Karlsson. In this patent the heat exchange element of a rotary regenerative heat exchanger is arranged in axially disposed banks in such a manner that fluid flowing through the heat exchange material is required to flow in a radial direction to make possible the use of a heat exchange element having a large surface area and a relatively shallow depth.

Such an arrangement directs the heating fluid and the fluid to be heated across each partition in a manner such that the hottest fluid contacts one end of the partition and the coldest fluid contacts the other. The resulting temperature differential at opposite ends of a metallic partition produces a variation of expansion that induces severe deformation of the partitions and connecting housing structure to greatly reduce its operating efficiency.

The present invention is directed to an improvement of the above described apparatus having a particular structure that directs hot fluid on one side of a metallic partition and cold fluid on the side laterally opposite whereby the temperature of the partition tends to approach a mean between the temperature of the heating fluid and the fluid to be heated that is approximately uniform throughout the partition. Thus, while each partition is free to expand or contract, with normal variations of temperature, the expansion will be uniform and not subject to distortion.

The invention will be more clearly described with reference to the embodiment thereof shown by way of example in the accompanying diagrammatic drawing in which:

FIGURE 1 is a partial top view of the heat exchanger utilizing the invention.

2

FIGURE 2 is an axial section of the rotary regenerative heat exchanger as seen from line 2—2 of FIGURE 1.

FIGURE 3 is a diagrammatic representation of thermal distortion in a rotor partition having a temperature gradient running from end to end.

FIGURE 4 is a diagrammatic representation of the even expansion of a rotor partition according to this invention wherein opposite sides of the same partition are subjected to opposite extremes of temperature.

In the drawing numeral 10 designates the cylindrical shell of a rotor divided into sector shaped compartments 11 by radial partitions 12 that connect to an axially central rotor post 14 which is driven by a gearing arrangement 16 and driving means (not illustrated) that turns the rotor slowly about its axis. The sector shaped compartments 11 are adapted to contain regenerative heat transfer material 24 which first absorbs heat from a heating fluid entering the regenerator through a duct 18 from a combustor or other source and is discharged through an outlet 22 after having passed through the bank of perforate heat transfer material 24. As the rotor turns slowly about its axis the heated material 24 is transported into a stream of the fluid to be heated that is admitted through duct 26. After passing over the heated material 24 and absorbing heat therefrom, the stream of heated fluid is conveyed through duct 28 to any predetermined place of use.

A housing 32 encloses the rotor and is provided at either end opposite the latter with end or sector plates 34 which are apertured as at 36 in alignment with ducts 18—22 and 26—28. In order that the streams of heating fluid and the fluid to be heated may be maintained in completely different ducts, sealing means are provided at the ends of the rotor to wipe against the sector plates of other fixed parts of the rotor housing.

Since the heating fluid and the fluid to be heated are usually directed through the heat exchanger in a counter-flow arrangement, the inlet for the heating fluid and the outlet for the heated fluid lie at adjacent ends of the rotor while the outlet for the cooled heating fluid and the inlet for the fluid to be heated lie at the same end of the rotor. Thus the rotor is divided into two basic temperature zones, the one which lies adjacent the inlet for the heating fluid being termed the "hot end" while that adjacent the inlet for the fluid to be heated is termed the "cold end" of the rotor. The radial partitions being part of the rotor are thereby subjected to a temperature differential that effect an expansion at the "hot end" in the manner illustrated in FIGURE 3. A series of such partitions formed into a rotor and similarly expanded by variations of temperature produces a serious degree of rotor distortion that precludes efficient rotor operation.

In accordance with the present invention the heat transfer material is supported in axially disposed banks intermediately the rotor shell and rotor post whereby laterally adjacent banks of material together form a composite annular mass of element concentric with the rotor axis. The annular bank of heat transfer material 24 is provided with a multitude of radially disposed perforations in order that fluid flowing between inlet and outlet ports is directed through the heat transfer material in a radial direction and in order that fluid will flow in radial opposite directions while traversing adjacent sectoral compartments, axial passageways 42 and 44 are provided with closure plates 46 at alternate ends thereof in the manner illustrated by FIGURE 2 of the drawing. By this arrangement, fluid entering a radial outer passageway 42 flows axially until it is turned radially inward through the bank of heat exchange material to the inner passageway 44. Here the fluid is again directed axially to continue its flow to the exhaust duct. Conversely, fluid en-

tering a radial inner passageway 44 flows axially until it is directed radially outward through the bank of heat exchange material to passageway 42 where it again is directed axially to the exhaust duct.

Thus while fluid is flowing radially outward through the bank of heat exchange material in one sectoral compartment, it is flowing through the banks of element in the adjacent compartments in a radially opposite direction in such a manner that opposite sides of each partition are subjected to opposite extremes of temperature. Thus the partitions tend to arrive at a mean between the average temperature of the heating fluid and the fluid to be heated. Under these conditions the diaphragms will expand evenly with the increase of temperature in the manner illustrated in FIGURE 4, there will be no variable expansion or distortion, and sealing surfaces will retain their original clearance settings.

While this invention has been described with reference to embodiment illustrated in the drawing, it is evident that numerous changes may be made without departing from the spirit of the invention. It is therefore intended that all matter contained in the above description or shown in the accompanying drawings shall be interpreted as illustrative and not in a limiting sense.

What we claim is:

Rotary regenerative heat exchange apparatus or the like having a rotor including a cylindrical rotor shell divided into sectoral compartments by partitions that extend radially from the rotor shell to an axially central

20 rotor post, and a housing surrounding the rotor shell provided at opposite ends with paired inlet and outlet ducts for the flow of a heating fluid and a fluid to be heated to and through the rotor; axially extending banks of perforate heat exchange material disposed similarly between partitions of adjacent compartments to provide a composite annular mass of heat exchange material concentric with the rotor axis; axial flow passageways adjacent the radial inner and outer sides of the banks of heat exchange material providing radial inner and outer passageways for the flow of fluid to and from the banks of heat exchange material; and closure means positioned at alternate ends of laterally adjacent passageways and at alternate ends of the radially inner and outer passageways adapted to direct fluid flow in radially opposite directions through banks of element lying in laterally adjacent compartments whereby laterally opposite sides of the radial partitions are subjected to opposite extremes of fluid temperature.
